UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

CONCRETE HANGER BLOCK.

Application filed February 10, 1927. Serial No. 167,182.

This invention relates to a block adapted to be embedded in a concrete structure and having an opening in the bottom for use in hanging pipes and other articles therefrom by means of a headed support projecting up into the interior of a hanger block.

The principal objects of the invention are to provide a hanger block which can be made of pressed metal instead of the usual casting, and have a relatively large flat bottom to furnish sufficient surface to allow of its being safely secured by an adhesive to a metal concrete floor form; to provide a block of pressed metal having ends set firmly between the sides and of such shape as to prevent the entrance of concrete to the nut cavity; to provide perforations in the bottom of the block for receiving nails to temporarily hold it in place while the concrete is being poured around it when used on wooden floor forms; to provide extensions on the sides projecting upwardly and preferably inclined towards each other and having flanges at their upper edges extending outwardly in opposite directions to firmly anchor the block in the concrete; and to avoid all waste by making the original blank in rectangular form and utilizing every particle of it.

The invention also involves the method of producing the hanger block and other features as will appear below.

Reference is to be had to the accompanying drawings, in which

Fig. 1 is a plan of the original blank as cut out for the production of this article;

Fig. 2 is an edge view showing the form of this blank after the first operation;

Fig. 3 is a plan of the same;

Fig. 4 is an end view showing the result of the next operation in which the ends are bent up into parallel position;

Fig. 5 is a similar view showing the result of the next operation;

Fig. 6 is a plan of the blank shown in Fig. 5;

Figs. 7 and 8 are views of a blank and an element made therefrom for assembling with the blank above referred to;

Fig. 9 is an end view showing the blanks of Figs. 6 and 8 assembled;

Fig. 10 is a section thereof on the line 10-10 of Fig. 9;

Fig. 11 is a view similar to Fig. 9 showing the next operation; and

Fig. 12 is a side view of the complete block embedded in concrete and supporting a hanger.

In Fig. 12, I have shown the complete article embedded in the concrete. It will be understood that when the concrete is being cast around it on a wooden support, the hanger block is held in position by two nails 10 or the like which are driven into a board 11 which constitutes the bottom of the mold for the concrete and is afterwards removed, leaving the nails projecting out. These nails hold the hanger block temporarily while the concrete is poured and they have no further function. Their ends are bent back out of the way by means of a hammer. This block can be used also when the support is metal instead of wood. For this purpose the bottom of the block is made with as large a surface as possible to take an adhesive which will hold it until the concrete has been poured and set. For this purpose the corners preferably are made square.

It will be seen that a rod 12 is shown depending from the hanger block held in position by a nut or the like 13 located within it. I will not describe the details of the hanger block with reference to Fig. 12 but will describe the process of manufacture, using the other figures for that purpose.

Fig. 1 shows the original rectangular flat blank. The blank is put in a press and shaped to the form shown in Figs. 2 and 3. It is provided with two ends 18 bent up at right angles, and preferably has a concave surface 14 across the center. Two pairs of parallel ribs 17 are also provided and two grooves 15.

The next operation is to bend this blank into the form shown in Fig. 4, in which the sides 16 are in parallel planes, with the concave body of the blank 14 between them and now constituting the bottom thereof. At this stage the corners are necessarily rounded.

In the next bending operation the concave bottom 14 is forced into a flat condition. As the sides 16 are combined in a die, the extra metal is forced out into the corners which become square as shown in Fig. 5. At the same time perforations 19

are made in the bottom to receive nails to hold the block on a wooden support while the concrete is poured. A hole 21 for admitting the pipe hanger nut into the completed block is also punched in the bottom. All this is shown in plan in Fig. 6.

Now a rectangular blank 20 is bent to provide two end flanges at right angles and inserted in the blank shown in Figs. 5 and 6. 10 between the ribs 17, as shown in Figs. 9 and 10, thus sealing the top and ends against the entrance of concrete.

Now the blank is put in other dies and the sides 16 bent toward each other as shown in 15 Fig. 11. The grooves 15 weaken the walls so that they will bend along those lines and not unduly compress or deform the piece 20.

The side walls 16 with the top edges of the ends 18 converge to form a concrete 20 wedge between them which aids to hold the block therein. This permits a solid body of concrete, integral with the concrete structure, to extend through the hanger block and thus 25 anchor it. The flanges 18 project out oppositely into the concrete to prevent any tendency of the block to pull away. The bottom is flat and, partly from having square corners, it furnishes a wide surface which can be made to adhere to a sheet 30 metal form by an adhesive and stand all the usual rough usage of concrete pouring, etc., without becoming detached. This is an important feature because the block may have to be attached either to a wooden or a metal 35 form, according to whichever type is used in the construction of the building.

Although I have illustrated and described only one form of the invention I am aware of the fact that changes can be made therein 40 by any person skilled in the art without departing from the scope of the invention as

expressed in the claims. Therefore I do not wish to be limited to the exact form shown, but what I do claim is:—

1. As an article of manufacture, a hanger block, adapted to be embedded in concrete, comprising a piece of sheet metal having a flat bottom with an opening therethrough for a fastening device, and a second sheet metal member bent into a U-shape and located entirely within the first member with its end edges resting on said bottom to close the space in the block, the two sides integral with the bottom projecting upwardly and encompassing the second member and having means, located entirely between the ends, for preventing the U-shaped member from moving to either end of the outer sheet metal piece, and projecting upwardly from the top of said second member and inwardly just at the top thereof to hold it securely in place and provided with anchoring features.

2. As an article of manufacture, a hanger block, adapted to be embedded in concrete, comprising a piece of pressed metal having a flat bottom with an opening therethrough for a fastening device, and a second sheet metal member bent into a U-shape with its end edges resting on said bottom to close the space in the block; the two sides integral with the bottom projecting upwardly and encompassing the second member and provided with integral vertical ribs near the ends to hold the second member in place and projecting upwardly from the top of said second member at opposite inclinations and provided with inclined diverging flanges to anchor the block in the concrete.

In testimony whereof I have hereunto affixed my signature.

HJALMAR G. CARLSON.
